DANCING SHOE

Filed Feb. 16, 1928

Inventor

Harold Rubin,
By his Attorney
Geo. A. Byrne

UNITED STATES PATENT OFFICE.

HAROLD RUBIN, OF NEW YORK, N. Y.

DANCING SHOE.

Application filed February 16, 1928. Serial No. 254,656.

This invention relates to improvements in dancing shoes usually worn by actors when dancing what is known as the clog and buck and wing dance; and it has for its object to produce a pleasing and noisy sound that will lend a great deal of novelty to a dancing act.

Another object of the invention is to provide a noise producing attachment that may be readily secured to the ordinary dancing shoe and which when in use will greatly facilitate the art of stage dancing of the eccentric type.

And to these ends the invention consists in the novel details of construction and combination of parts more fully hereinafter described and particularly pointed out in the claims.

Referring to the drawings forming a part of this specification, in which like numerals 20 designate like parts in all the views:—

Figure 1 is a side elevational view of a shoe showing the invention secured thereto.

Figure 2 is an enlarged bottom plan view of the toe portion of the shoe.

Figure 3 is an enlarged side elevational view, with a part broken away, of the toe portion of the shoe.

Figure 4 is an enlarged detail cross sectional view of a portion of the shoe attachment, and,

Figure 5 is a side elevational view of the parts shown in Figure 4.

Referring to the drawings in detail, 1 designates a shoe of the type generally used by dancers and 2 designates my improved attachment secured to the sole 3 at the toe portion.

The attachment comprises a pair of horizontally arranged steel plates 4 and 5 which are connected together at a plurality of points by a series of rivets 6. Spacing washers 7 surround the rivets between the plates, for holding the plates in proper spaced relation to each other. The upper or top plate 4 is relatively larger than the lower or bottom plate 5 and is formed from a relatively thin piece of steel and is provided, adjacent its outer edge, with a series of openings 8 through which pass a series of nails 9 for securing the attachment to the sole 3 of the shoe.

The lower or bottom plate 5 is formed from a relatively thick piece of steel and is provided with a series of recesses or sockets 10

for retaining a plurality of steel balls 11. The balls are loosely mounted within the sockets so as to have a vertical movement or upward and downward play when the device is in use. The balls are arranged to project slightly below the bottom surface of the plate 5 and during the act of dancing when the foot contacts with the floor the balls are suddenly driven upwardly into contact with the plate 4, as shown in Figure 5, thus producing a pleasing and noisy sound.

In securing the device to a shoe an opening 12 is cut in the sole to conform to the size and shape of the plate 5. The device is then secured in position and arranged so that the upper plate 4 will be secured to the shoe between the outer sole 3 and the inner sole 13, as shown in Figure 3. When secured in position the bottom surface of the plate 5 is flush with the bottom surface of the sole of the shoe so that a smooth and continuous surface of the plate and sole is presented.

By the provision of a ball bearing attachment of this type it is obvious that the art of stage dancing may be somewhat facilitated and quicker and more graceful movements obtained in rendering a new and novel dancing act.

While I have described in detail specific forms of the invention, I wish it to be understood that various modifications and changes 85 may be made, such as for instance, the attachment may be secured to the heel of the shoe if desired or to the central or any other part of the sole if desired.

What I claim is:—

1. An attachment for dancing shoes comprising a pair of horizontally arranged plates adapted to be secured to the sole of the shoe and a plurality of sound producing elements loosely mounted on one of the plates and adapted to strike the other of said plates when the shoe is used in dancing.

2. An attachment for dancing shoes comprising a pair of horizontally arranged plates secured to each other in spaced relation and a plurality of sound producing elements loosely mounted in the lower plate and arranged to strike the upper plate when the shoe is used in dancing.

3. An attachment for dancing shoes comprising a pair of horizontally arranged plates secured to each other in spaced relation, the lower of said plates being provided

- with a series of recesses and a series of sound producing elements loosely mounted in the recesses and arranged to strike the upper plate when the shoe is used in dancing.
- 5 4. An attachment for dancing shoes comprising a pair of horizontally arranged plates secured to each other in spaced relation, the lower of said plates provided with a series of recesses, and balls loosely mounted in the recesses and projecting below the bottom surface of the lower plate, said balls being arranged to strike the upper plate when the shoe is used in dancing.
- 10 5. In a dancing shoe having its sole provided with an opening, a pair of horizontally arranged plates secured to the shoe within the opening, and a plurality of sound producing elements loosely mounted in one of the plates and adapted to strike the other 20 of said plates when the shoe is used in dancing.
6. In a dancing shoe having its sole provided with an opening, a pair of horizontally arranged plates secured to the shoe within the opening, and a plurality of balls loosely mounted in the lower of said plates and adapted to strike the upper of said plates when the shoe is used in dancing. 25
7. In a dancing shoe having its sole provided with an opening, a pair of horizontally arranged plates connected to each other in spaced relation and secured to the shoe within the opening, and balls loosely mounted in the lower of said plates and having a portion projecting below the bottom surface 30 of the plate, said balls being arranged to strike the upper plate when the shoe is used in dancing. 35

In testimony whereof I have hereto affixed my signature on this 14th day of February, 1928. 40

HAROLD RUBIN.
